[57] CLAIM

The ornamental design for a combined electric guitar,
amplifier and speaker, as shown.

DESCRIPTION

FIG. 1 is a top front perspective view of a combined
electric guitar, amplifier and speaker showing my new
design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The neck of the guitar is shown fragmentarily for ease
of illustration.

FIG. 1
